UNITED STATES PATENT OFFICE

153,923

DESIGN FOR LAUNDRY TONGS

Paul H. Brown, Sr., Detroit, Mich.

Application October 15, 1948, Serial No. 149,118

Term of patent 14 years

(Cl. D49—1)

To all whom it may concern:

Be it known that I, Paul H. Brown, Sr., a citizen of the United States, residing at Detroit, in the county of Wayne and State of Michigan, have invented a new, original, and ornamental Design for Laundry Tongs, of which the following is a specification, reference being had to the accompanying drawings, forming a part thereof.

Figure 1 is a face view of laundry tongs showing my new design;

Figure 2 is a left hand end elevational view of Figure 1;

Figure 3 is a right hand end elevational view of Figure 1;

Figure 4 is a bottom edge elevational view of Figure 1.

I claim:

The ornamental design for laundry tongs, as shown.

PAUL H. BROWN, SR.
